CLAIM

The ornamental design for a motor conduit plug, as shown and described.

DESCRIPTION

FIG. 1 is a side perspective view of a motor conduit plug embodying our design and being depicted as part of a motor for environmental purposes.

FIG. 2 is a side perspective view of only the motor conduit plug as depicted in FIG. 1;

FIG. 3 is a side perspective view of the motor conduit plug depicted in FIGS. 1 and 2 taken from the opposite angle, with the motor conduit plug being depicted as part of the motor.

FIG. 4 is a side perspective view of only the motor conduit plug as depicted in FIG. 3;

FIG. 5 is a bottom perspective view of the motor conduit plug shown in FIGS. 1-4;

FIG. 6 is a top perspective view of the motor conduit plug shown in FIGS. 1-5;

FIG. 7 is a side elevation view of the motor conduit plug shown in FIGS. 1-6, with the opposite side elevation being a mirror image thereof;

FIG. 8 is a side elevation view of the motor conduit plug taken at a ninety degree (90) angle relative to that shown in FIG. 7, with the opposite side elevation being a mirror image thereof;

FIG. 9 is a top elevation view of the motor conduit plug shown in FIGS. 1-8; and,

FIG. 10 is a bottom elevation view of the motor conduit plug shown in FIGS. 1-9.

The broken lines depict environmental subject matter only and form no part of the claim.
